UNITED STATES PATENT OFFICE.

SIMON COOPER, OF BROOKLYN, NEW YORK.

CONTAINER AND CLOSURE CONNECTION.

Application filed May 6, 1921, Serial No. 467,324. Renewed April 14, 1926.

This invention relates to means for permanently attaching a closure member to an object while permitting the unrestricted attachment of the member in, or its removal 5 from, its functioning position.

In order to prevent the misplacement and loss of removable cover members such, for instance, as the relatively small screw caps used in connection with collapsible container 10 tubes, caps have heretofore been secured to the tubes by means of sections of wire attached at one end to an eye on the tube and at the other end looped around the periphery of the cap. This construction has 15 been unsatisfactory in practice because of the interference of the connecting wire with the fitting of the cap to the threaded nozzle of the tube and with the rotation of the cap while in engagement with the threads.

20 It is an object of this invention to provide retaining means for use in connection with cover members of the general type referred to which will not interfere with the manipulation of the cover member and 25 which, in addition, will provide in a simplified construction, a device which will hold the cap with an increased and more effective degree of security.

It has been found that the referred to 30 interference with the manipulation of the screw cap can be obviated by making use of a flexible retaining member having one end attached to the body of the tube and the other end attached to the outer end of 35 the screw cap substantially in alignment with the axis of rotation thereof. This arrangement not only leaves the peripheral margins of the cap wholly free for engagement by the fingers of the user, but any 40 force that may be exerted on the flexible connector is in the form of a harmless twist or rotation instead of an objectionable pulling or tugging strain.

Another feature of the invention resides 45 in the simple and effective means employed for attaching the ends of the flexible connecting member to the tube and to the cap member. This feature includes recesses or pockets formed in the tube and the cap in 50 the same operation in which the parts are themselves produced, the recesses being arranged to receive enlargements formed on the ends of the flexible connector. The enlarged ends of the connector are held in 55 place in the recesses preferably by upsetting the edge or otherwise restricting the

size of the entrance end of each recess after the ends of the connector have been placed in the pockets.

The flexible connector in a preferred form 60 of the invention consists of a length of metal chain of a well-known type in which the links have universal joint connections with each other, so that an unrestricted turning movement of the cap to which one end of 65 the flexible connector is attached is permitted. In another form of the invention the flexible connector may take the form of a member in which a sufficient torsion or twist may be produced to effect the required 70 rotation of the cap member. Preferably the flexible connector has a length such that it may be used as a means for suspending the container from a holder.

In the drawing:

Figure 1 is a side view of the discharge 75 end of a collapsible tube container equipped with a cover retaining device embodying a preferred form of the invention;

Figure 2 is a sectional view of the de- 80 vice shown in Figure 1;

Figure 3 is an end view of the device shown in Figure 1 looking to the right;

Figure 4 is an end view of a cap for the 85 container before the retainer member is attached thereto;

Figure 5 is a view in cross section of the 90 cap shown in Figure 4;

Figure 6 is a view similar to Figure 2 showing a modified form of cover-retaining 95 device;

Figure 7 is a view similar to Figure 6 and showing still another form of retaining device.

Referring to the drawings, there is shown 95 a portion of a collapsible tube container 1 having an ordinary form of threaded discharge spout 2 which is adapted to be closed by means of the screw cap cover 3. In order to provide for attaching the cap 100 member 3 to the tube in such manner that misplacement or loss of the cap is prevented, a flexible connecting member 4 is provided which is attached at its ends to the cap 3 and to a point in the shoulder 5 of the 105 tube 1. Preferably the connecting member 4 takes the form of a well known type of chain commonly used with pull-chain electric lamp sockets and which can be freely twisted or rotated by reason of a form of universal joint connection between the links.

Provision is made for attaching the flexi-

ble connector to the cap member 3 by producing a recess or pocket 6 in the cap, preferably in the same operation in which the cap is itself formed. The pocket 6 is of such size as to receive one of the terminal ball members of the chain 4, whereupon the entrance edge of the pocket is upset or turned inwardly to lock the ball in place in the pocket as shown at 7 in Figure 2 of the drawing.

The other end of the flexible connector 4 is held in place at its point of attachment to the tube 1 in the same general way, that is, a recess or pocket 8 is formed in the shoulder 5 of the tube, the end of the chain 4 is placed in the pocket, and the entrance edges of the pocket 8 are turned inwardly to permanently enclose the terminal ball of the chain in the pocket. It will be seen that a retaining device for the cap 3 of the collapsible tube 1 is thus provided which will permit of the rotation of the cap in relation to the threaded spout 2 of the container, and that the length of the flexible connector 4 is such as to provide a convenient means of suspension of the entire container from a hook or similar support.

In Figure 6 of the drawing a similar result is obtained by means of a flexible connecting member 9 formed preferably of a short length of wire having enlarged end members 10 which can be conveniently anchored in the corresponding pockets 6 and 8 in the cap 3 and tube shoulder 5, as in the form of the invention already described. The length of wire 9 either single or stranded permits of sufficient torsion or twist to provide for the necessary rotation of the cap member 3.

In Figure 7 of the drawing still another form of connector is shown as taking the form of a simple helically coiled wire having its opposite ends anchored in the pockets 6 and 8. With this form of connector enlarged end members are dispensed with and the entrance ends of the pockets are up-

set to lock a number of the terminal convolutions or windings of the coil in place in the pockets.

I claim:—

1. In combination with a container having a rotatable cover the outer end of which is provided with a pocket, a flexible connector having one end attached to the container, the other end of said connector being enlarged and seated in the pocket in said cover, and the entrance of said pocket being upset to anchor said enlarged end of said connector in said pocket.

2. In combination with a collapsible tube container having a screw cap cover, a flexible connector having one end attached to the end of said screw cap cover, the other end of said connector being enlarged, the shoulder of said container being provided with a pocket to receive the enlarged end of said connector, and the entrance of said pocket being upset to anchor said enlarged end of said connector in said pocket.

3. In a device of the class described, a container having a threaded neck portion formed thereon, and also having a closed-bottomed socket formed on the exterior thereof adjacent the neck portion, a screw cap for the container also provided with a socket, a flexible connection, and members carried at the ends of the connection and held, respectively, in the sockets of the cap and container.

4. In a device of the class described, a container having a threaded neck portion formed thereon, and also having a closed-bottomed socket formed on the exterior thereof adjacent the neck portion, a screw cap for the container also provided exteriorly thereof with a closed-bottomed socket, a flexible connection, and members carried at the ends of the connection and held, respectively, in the sockets of the cap and container.

In testimony whereof I affix my signature.
SIMON COOPER.
